UNITED STATES PATENT OFFICE.

FRANK A. GAUGER AND ROY W. JOHNSON, OF MILWAUKEE, WISCONSIN.

FLASH IGNITER.

1,417,510.

Specification of Letters Patent. Patented May 30, 1922.

Application filed December 6, 1920. Serial No. 428,569.

To all whom it may concern.

Be it known that we, FRANK A. GAUGER and ROY W. JOHNSON, both citizens of the United States, and residents of Milwaukee, in the county of Milwaukee and State of Wisconsin, have invented certain new and useful Improvements in Flash Igniters; and we do hereby declare that the following is a full, clear, and exact description thereof.

10 Our invention relates to new and useful improvements in flash igniters for use in connection with the burners of gas stoves and the like, and includes the usual constant burning pilot light, a cover therefor and a valve for controlling the flow of gas.

15 It is one important object of this invention to provide a very simply constructed flash igniter valve which, because of the fact that it is formed of a fewer number of parts than the usual valve of this character, may be quite inexpensively manufactured.

20 A further object of the invention is to provide a simple and new arrangement of parts of a valve of this character for providing the necessary continuous limited flow of gas for the pilot light.

25 An additional important object of the invention is to provide an improved covering for the torch-head of the device which, while effectively protecting the pilot light, may be cheaply made from a single metal blank or from a casting.

30 In further reducing the cost of manufacture, which is one of the fundamental principles of this invention, the torch head is disposed horizontally and mounted directly on the end of the supply pipe from the control valve and forms a support for its protective covering.

35 40 With these and other objects in view the invention resides in the novel features of construction, combination and arrangement of parts which will be hereinafter more particularly described and claimed.

45 In the accompanying drawings

Figure 1 represents a vertical sectional view through portions of a flash igniter assembly constructed in accordance with our invention, and

50 Figure 2 is a plan view of the protective covering or canopy of the torch-head.

Referring more particularly to the draw-

ing, it will be seen that the valve structure of our invention includes a body casting 1 having a normally vertically disposed transversely formed well 2 intermediate its ends, into which ports 3 and 4 enter from said ends. The inner ends of the ports 3 and 4 communicate with the well 2 at points spaced longitudinally thereof, and midway between these points the preferably cylindrical wall of the well 2 is provided with an annular shoulder 5 forming a valve seat. The port 4 is adapted to communicate with a main supply pipe, whereas the other port 3 opens into the adjacent end of a branch supply pipe 6, the same being threaded into the body casting 1 and supported thereby.

The upper or outer portion of the wall of the well 2, above the point of entrance of the port 3 thereinto is screw-threaded to receive the intermediately threaded portion of a sleeve plug 7. The inner end portion of the plug 7 has its peripheral surface shaped to provide an annular valve head member 8 for co-operation with the valve seat 5. Thus by threading the sleeve plug 7 inwardly or outwardly of the well 2, this portion 8 is varied in its relation to its cooperating valve seat 5. Between said valve head portion 8 and the screw-threads of the sleeve plug 7, the latter is provided with an annular recess 9 which registers with the port 3 and has openings 10 communicating therewith, which openings are formed through the wall 85 of the sleeve plug from the bore thereof.

Movable longitudinally within the bore of the sleeve plug 7 is a valve-stem 11, the same having a valve-head 12 on its inner end for co-operation with the similar end of the 90 sleeve-plug as shown in Figure 1. The outer end of the stem 11 carries a push-button 13, one portion of which is reduced in diameter and slides within the sleeve plug 7, this portion also having one end of an expandable coiled spring 14 disposed thereagainst for normally urging the button 13 outwardly, the other end of said spring being disposed against a packing washer 15 in the bore of the plug 7.

The end of the supply pipe 6 opposite its connection with the body 1 of the valve structure has a torch-head 16 carried thereby, the axis of which torch-head is disposed

- horizontally and is coincident with the center line of said supply pipe. Thus the several flash openings 17 are located in a horizontal plane. Said torch-head 16 is in effect merely a tip having an enlarged attaching portion 18 which is threaded over the end of said supply pipe and is also externally screw-threaded for the attachment of a torch-head protective covering or canopy 19.
- 10 In the present instance this canopy is disk-like in shape with slightly downturned edges and is located only a short distance above the torch-head 16 so as to protect the same from liquids or other materials which 15 may be dropped into the stove. The canopy is mounted in this position by an arcuate attaching plate portion 20 which depends from one part of the downturned edge thereof and is provided with a flanged opening, 20 the wall of which opening is screw-threaded for engagement with the attaching portion 18 of the torch-head.
- In operation the flash igniter assembly consisting of the parts hereinbefore described is located so that the torch-head 16 will be in a position to permit the simultaneous lighting of several stove burners, if necessary. Owing to the by-pass valve formed within the well 2 by the valve seat 5 30 and the valve head portion 8, a limited supply of gas is permitted to continuously flow from the port 4 to the port 3 and thence by way of the supply pipe 6 to the torch head 16. When, however, the button 13 is depressed and the valve head 12 moved away from the inner end of the sleeve plug 7, a full supply of gas is permitted to enter the supply pipe 6 so that jets of flame are projected from each of the several flash openings 17. Certain of said jets of flame are projected through notches 21 in the opposite side edges of the attaching plate portion 20 of the canopy 19. Upon release of the button 13 the main flow of gas is cut off and 45 only the pilot flames burn at the torch-head.
- We claim:
1. A valve of the class described comprising a body provided with a well and with ports communicating with said well at points spaced longitudinally of the well, a valve sleeve plug engaged in the well and terminating short of the inner port and provided in its periphery with an annular recess registering with the other port, and further provided with an 50 opening at said recess, the peripheral surface of the inner end portion of the plug having an annular valve head portion for co-operation with the said annular valve seat whereby to permit a continuous limited flow of 55 fluid between said ports, a valve stem movable through said sleeve plug, and a head on the stem co-acting with the inner portion of the sleeve 60 plug.
  2. A valve of the class described comprising a body provided with a cylindrical well and with ports communicating with said well at spaced points, a valve plug disposed in said well and having a fluid pas- 65 sageway therethrough, said plug co-operating with a portion of the wall of the well to permit a continuous limited flow of fluid from one of said ports to the other, and a valve head disposed in the passageway of 70 said plug for controlling the main flow of fluid between said ports.
  3. A valve of the class described comprising a body provided with a cylindrical well and with ports communicating with said well at spaced points, a valve plug disposed in said well and having a fluid passageway therethrough, the inner end portion of said plug co-operating with a portion of the wall of the well to permit a continuous limited 75 flow of fluid from one of said ports to the other, said plug being adjustable in said well to vary the co-action between its inner end portion and the well wall portion to regulate said limited fluid flow, and a valve head 80 disposed in the passageway of said plug for controlling the main flow of fluid between said ports.
  4. A valve of the class described comprising a body provided with a cylindrical well and with ports communicating with said well at spaced points, the well wall having an annular shoulder forming a valve seat, a valve plug disposed in said well and having an annular valve head portion co-operat- 85 90 95 ing with said valve seat to permit a continuous limited flow of fluid from one of said ports to the other, said valve plug being adjustable in the well to vary the amount of said limited flow, said valve plug also having a fluid passageway therethrough, and a valve head disposed in the passageway of the plug for controlling the main flow of fluid between said ports.
  5. A valve of the class described comprising a body provided with a cylindrical well and with ports communicating with said well at points spaced longitudinally of the well, the wall of said well having an annular shoulder disposed between said ports and 100 forming a valve seat, a valve sleeve plug engaged in said well and terminating short of the inner port and provided in its periphery with an annular recess registering with the other port, and further provided with an 105 opening at said recess, the peripheral surface of the inner end portion of the plug having an annular valve head portion for co-operation with the said annular valve seat whereby to permit a continuous limited flow of 110 fluid between said ports, a valve stem movable through said sleeve plug, and a head on the stem co-acting with the inner end of the sleeve plug.
  6. In a flash igniter for gas burners, the combination with a plurality of burners, of an auxiliary supply pipe, a flash igniter valve connecting said auxiliary supply pipe with a source of gas supply, and a torch-head on the end of said supply pipe remote from 115 120 125 130

its connection with the valve, said torch-head having its axis disposed substantially horizontally and having flash openings in the end and sides thereof arranged in a horizontal plane to project diverging jets of flame upon actuation of said valve to play on said burners.

In testimony that we claim the foregoing we have hereunto set our hands at Milwaukee, in the county of Milwaukee and 10 State of Wisconsin.

FRANK A. GAUGER.
ROY W. JOHNSON.

DISCLAIMER.

1,417,510.—*Frank A. Gauger and Roy W. Johnson, Milwaukee, Wis. FLASH IGNITER.* Patent dated May 30, 1922. Disclaimer filed August 1, 1923, by the assignee, *Milwaukee Gas Specialty Co.*

Hereby enters this disclaimer to claim 1, which is in the following words, to wit:

“1. A valve of the class described comprising a body provided with a well and with ports communicating with said well at points spaced longitudinally of the well, a valve sleeve plug engaged in the well and terminating short of the inner port and provided in its periphery with an annular recess registering with the other port and further provided with openings at said recess, the sleeve plug being reduced in bore outwardly of the ports, a valve stem movable through said reduced bore portion, and a head on the stem co-acting with the inner portion of the sleeve plug.”
